[57] CLAIM

The ornamental design for reflective camera flash attachment, as shown and described.

DESCRIPTION

FIG. 1 is a front elevational view of a reflective camera flash attachment showing my new design in a ready to mount condition;

FIG. 2 is a left side elevational view thereof;

FIG. 3 is a right side elevational view thereof;

FIG. 4 is a top plan view thereof;

FIG. 5 is a rear elevational view thereof;

FIG. 6 is a bottom plan view thereof;

FIG. 7 is a front perspective view thereof;

FIG. 8 is a front elevational view with the camera flash attachment mounted on the flash unit;

FIG. 9 is a front elevational view thereof, in an unassembled condition shown for clarity of illustration; and FIG. 10 is a front elevational view thereof, in a fully assembled condition.

The broken line showing of the flash unit is for illustrative purposes only and forms no part of the claimed design.
